UNITED STATES PATENT OFFICE.

CHARLES A. VALENTINE, JR., OF YONKERS, NEW YORK.

COMPOUND RESONATOR.

1,282,500.

Specification of Letters Patent. Patented Oct. 22, 1918.

Application filed November 23, 1916. Serial No. 132,961.

To all whom it may concern:

Be it known that I, CHARLES A. VALENTINE, Jr., a citizen of the United States of America, and a resident of Yonkers, West-
chester county, and State of New York, have invented certain new and useful Improve-
ments in Compound Resonators, of which the following is a specification, reference be-
ing had to the accompanying drawings,
10 forming a part thereof.

My invention relates to improvements in compound resonators and its object is to provide a simple and efficient device which is extremely responsive to sound vibrations
15 and capable of effectively augmenting such vibrations.

In order that my invention may be thoroughly understood I will now proceed to describe the same in the following specification, and then point out the novel features thereof in appended claims.

Referring to the drawings:

Figure 1 is a sectional side elevation of an amplifying horn provided with a plurality of compound resonators which are made according to and embodying my invention.

Fig. 2 is a plan view, and Fig. 3 a front elevation of one of the compound resonators shown in Fig. 1.

In Fig. 4 I have shown in plan view, a modified form of resonator which also embodies my invention.

Fig. 5 is a front elevation of the form of resonator which is shown in Fig. 4.

Fig. 6 is a sectional side elevation of another form of resonator which is also made according to this invention.

Fig. 7 is a perspective view of another modification of construction, and

Fig. 8 is a sectional front elevation of a still further modified structure embodying the same invention.

Like characters of reference designate corresponding parts in all the figures.

10 designates a flat board of thin wood or other vibrating material upon which the other parts of the apparatus are mounted. 11 are supporting bridges which in the structure shown in Figs. 1, 2 and 3, run longitudinally across the center of the board 10 on opposite sides thereof. Across the outer surfaces of these bridges and disposed transversely in relation therewith are a plurality 55 of parallel vibrators 12. Outside of these

are clamping strips 13 and all of these parts are held together rigidly by through bolts 14.

The vibrators 12 are preferably constructed of thin strips of material sensitive to sound vibrations, such for example, a wood 60 carefully seasoned and prepared for this purpose. These are of different dimensions so as to be responsive each to vibrations of different frequencies. A convenient means for attaining this result is to make them of 65 different lengths and to offset them centrally on the bridges.

In Fig. 1 four of these improved compound resonators are shown in an amplifying horn 20 of a form suitable for use in 70 conjunction with a phonograph or talking machine. At the smaller end of this horn is an inlet opening 21 surrounded by a wooden frame 22 by means of which the horn may be affixed to a similar frame 23 at the mouth 75 of an adapter 24, the other end of which may be affixed to the sound emitting opening of a phonograph or talking machine (not shown).

The sound vibrations pass through an 80 opening between two deflectors 25 but some of them are deflected to the curved surfaces 26 of the horn which reflect them so that they pass out through the mouth of the horn. Thus the sound vibrations pass 85 through different paths through the horn so that a plurality of my sounding boards may be used to advantage with such a horn.

The operation of the resonator may be understood from the foregoing description of 90 the form of construction illustrated in the first three figures of the drawings. The vibrators 12 are each responsive to one frequency and most if not all of them are independently responsive to different frequencies. Thus, when the device is placed in the path of a musical or other sound, many of these vibrators are set in motion thereby and tend to lengthen, sustain, and augment the vibrations of the impressed sound waves. 100 The presence of the base board 10 in proximity to the vibrators further increases this effect by reflecting the vibrations.

As the vibrators are tuned to definite periods of vibration preferably all within the 105 range of audibility, there is another important function performed by them, in that certain undesirable irregular vibrations, such as those produced by the scratch of a phonograph needle, are not augmented so 110

that in effect they are proportionately reduced or eliminated.

In the structure shown in Figs. 4 and 5, 10^A designates the base board. In this case 5 the bridges 11^A are set along the opposite edges of the board. The vibrators 12^A are secured to the bridges by means of clamping strips 13^A and through bolts 14^A as in the previously described construction, but in 10 this case each is secured near one of its ends so that a separate piece is required for each vibrator.

The operation of this embodiment of my 15 invention is so similar to that previously described that it would be superfluous to repeat a description of it.

It is obvious that the base board need not be plane but that my invention is applicable to a parabolic or curved sounding board 20 such as that shown at 10^B in Fig. 6. In this case the bridge 11^B and the clamping strip 13^B are curved to conform with the shape of the base board 10^B. The vibrators in this figure are designated 12^B.

25 In the structure shown in Fig. 7, the base board 10^C is plane, and the bridge 11^C is placed across its surface. The vibrators 12^C are held between the bridge and a clamping strip 13^C, but in this case they are placed 30 normal to the board 10^C instead of parallel therewith as in the other cases. These vibrators have much the same operation as that described in connection with the structure of Figs. 1, 2 and 3, except that there 35 is not the same reflex action between them and the base board.

In the structure of Fig. 8, a plurality of rows of parallel vibrators 12^D are shown between bridges 11^D and clamping strip 13. 40 held together and to base board 10^D by through bolts 14^D.

I have illustrated and described several structures embodying my invention to show that it is not limited to any specific construction or use but that it is in fact capable of wide variation within its spirit and scope. In fact, I intend no limitations other than those imposed by the appended claims.

What I claim is:

50 1. A compound resonator comprising a base board, a plurality of vibrators of unlike dimensions supported by but spaced from said base board, each in parallel relation with said base board.

55 2. A compound resonator comprising a base board, a bridge thereon, and a plurality

of vibrators of unlike dimensions held by said bridge away from and in parallel relation with said base board.

3. A compound resonator comprising a 60 base board, a bridge thereon, and a plurality of flat vibrators of unlike dimensions held by said bridge away from and in parallel relation with said base board and with one another.

65 4. A compound resonator comprising a base board, a bridge thereon, and a plurality of flat vibrators of unlike dimensions upon said bridge and supported thereby away from and in parallel relation with said base board and with one another, and means for holding said vibrators, bridge and base board together.

70 5. A compound resonator comprising a base board, a plurality of bridges thereon, and a plurality of vibrators of unlike dimensions held by said bridges away from and in parallel relation with said base board.

75 6. A compound resonator comprising a 80 base board, a plurality of bridges thereon in alignment with one another, and a plurality of vibrators of unlike dimensions held by said bridges away from and in parallel relation with said base board.

85 7. A compound resonator comprising a base board, a bridge thereon, and a plurality of vibrators of unlike dimensions held intermediate their ends by said bridge away from and in parallel relation with said base 90 board.

95 8. A compound resonator comprising a base board, a plurality of bridges thereon in alignment with one another, a plurality of flat vibrators of unlike dimensions held by said bridges intermediate their ends away from and in parallel relation with said base board and with one another, and means for holding said vibrators, bridges, and base board together.

100 9. A compound resonator comprising a base board, bridges each side of said base board in alignment with each other, a plurality of flat vibrators of unlike dimensions held by said bridges intermediate their ends away from and in parallel relation with said base board and with one another, and means for holding said vibrators, bridges, and base board together.

110 In witness whereof I have hereunto set my hand this 20 day of November, 1916.

C. A. VALENTINE, JR.
